UNITED STATES PATENT OFFICE.

GEORGE F. WEHR, OF ROCHESTER, PENNSYLVANIA, ASSIGNOR TO PHOENIX GLASS COMPANY, OF PITTSBURGH, PENNSYLVANIA, A CORPORATION OF WEST VIRGINIA.

LAMP.

1,040,072.

Specification of Letters Patent.

Patented Oct. 1, 1912.

Application filed February 20, 1911. Serial No. 609,823.

To all whom it may concern:

Be it known that I, GEORGE F. WEHR, a citizen of the United States, and resident of Rochester, in the county of Beaver and 5 State of Pennsylvania, have invented a new and useful Improvement in Lamps; and I do hereby declare the following to be a full, clear, and exact description thereof.

My invention relates to lamps, its object 10 being to provide a lamp so constructed that the shade may be supported in position on the lamp without the employment of any brass or metal fittings, thereby greatly enhancing the appearance of the lamp and 15 at the same time reducing the cost.

To these ends my invention consists, generally stated, in a lamp comprising a hollow glass stand having an outwardly flaring upper end portion and a shade adapted 20 to rest upon the upper end of said flaring portion and extending outwardly beyond said point of support, together with means for supporting an electric, gas or other burner in said stand.

25 In the accompanying drawings Figure 1 is a side elevation of my improved lamp; Fig. 2 is a vertical section; Fig. 3 is a view of the lamp stand partly broken away; and Fig. 4 is a section on the line 4—4 30 Fig. 2.

In the drawings the numeral 2 designates the stand which is preferably formed from glass by blowing the same in a suitable mold so that said lamp stand will be hollow as indicated in Fig. 2. The shape of the stand may be varied as desired according to the design to be produced and as the mold for forming the same forms no part of my invention, it has not been deemed necessary 35 to illustrate the same, it being sufficient to say that the stand may be blown in an ordinary paste mold, said mold being formed to produce the outwardly flaring portion 3. This flaring portion 3 may be 40 provided with the straight or vertical edgeportion 4, and the shade 5 of any suitable design is supported directly upon the edge portion 4 of the flaring portion 3 of the stand. The shade 5 may be formed with a

shoulder 6 which rests on the edge portion 50 4 and in this way the shade is firmly supported and held against displacement. Where my improved lamp is to be used in connection with an electric burner, the socket 7 is supported by the fingers 8 which 55 rest upon the inner face of the flaring portion 3 at the lower end thereof and connected to the socket is the cord 9 which passes down through the hollow stand and out through the opening 10. The incan- 60 descent bulb 11 is inserted in the socket 7 and extends up within the flaring portion 3 of the stand.

In order to conceal from view the cord 9 and socket 7 I prefer to frost the stand up 65 to a point even with the upper end of the socket, leaving the flaring portion 3 of plain glass so that the full strength of the light will be obtained. The shade 5 is also preferably frosted so as to conceal the bulb and 70 when the lamp is lighted there is nothing to mar the continuity of the effect of the glass, as the bulb is entirely concealed together with the socket and cord, and as the shade is supported directly on the lamp 75 stand, no brass rings or fittings are required to support the shade. The lamp when lighted gives a very rich, handsome appearance, and by the fact that no supporting bracket engages the lower edge of the 80 shade, the shade may be scalloped as at 12, or be given any other decorative design.

What I claim is:

1. A lamp comprising a hollow glass stand having an outwardly flaring portion formed 85 integrally therewith and a shade supported directly on said flaring portion extending outwardly beyond said point of support.

2. A lamp comprising a stand having a flaring upper end portion, and a shade hav- 90 ing a shoulder on its inner face with which the upper end of said stand engages.

In testimony whereof, I the said GEORGE F. WEHR, have hereunto set my hand.

GEORGE F. WEHR.
